UNITED STATES PATENT OFFICE.

JAMES W. RUMSEY, OF WEST BERKELEY, CALIFORNIA, ASSIGNOR OF ONE-HALF TO
FRANK T. HAYS, OF CHICAGO, ILLINOIS.

BOX-CAR-DOOR STRUCTURE.

1,215,716.

Specification of Letters Patent. Patented Feb. 13, 1917.

Application filed July 14, 1915. Serial No. 39,830.

To all whom it may concern:

Be it known that I, JAMES W. RUMSEY, a citizen of the United States of America, and a resident of West Berkeley, county of 5 Alameda, State of California, have invented certain new and useful Improvements in Box-Car-Door Structures, of which the following is a full and clear specification, reference being had to the accompanying drawings, in which—

Figure 1 is a side elevation of a portion of the side of a box-car showing my invention applied thereto; and

Fig. 2 is a horizontal section on the line 15 2—2 of Fig. 1.

This invention has relation to that type of car-door which slides back and forth across the door-opening in the side wall of the car and the object of this invention is to provide simple means which will insure a water-tight joint or seal at the front edge of the door when the door is closed and which at the same time will greatly increase the rigidity of the door, especially along 25 its front edge, as more fully hereinafter set forth.

In the drawing *a* designates the side wall of the car, *b* the post at the left-hand side of the door-way, and *c* a portion of the 30 front edge of the sliding door. The front corner of the front edge of the door is rabbeted and secured in this rabbet or recess and extending the full height of the door is a metal plate *d*, the securing means being 35 preferably a series of bolts *e* which pass through the plate and through the door. The front edge of this plate is provided with a flange or extension *f* which extends over upon the front edge of the door the full 40 thickness of the door, its inner edge terminating approximately flush with the inner face of the door. These two integrally connected plates *d* and *f* form an angle iron which extends the full height of the door 45 and therefore serve to greatly strengthen and stiffen the door along its front edge. The thickness of the plate *d* is about one-half that of the rabbet in the door, and at the left-hand edge of the plate *d* an outwardly extending integral flange *g* is 50 formed, the outer wall or face of which abuts against the shoulder *h* formed by the rabbet in the door.

In the body of the door-post *b* is a metal

plate *i*, this plate being clamped between 55 the vertical members *j* and *k* comprising the main part of the post. This plate *i* runs the full length of the door-post and has its front edge projecting a distance beyond the member *j* of the post equal to the thickness 60 of the door *c*, and along said projecting outer edge is formed an integral flange *l* which, when the door is closed, overlaps upon the plate *d* and has its front face flush with the front face of the door. The free 65 edge of the flange or plate *d* abuts against the flange *g*, so that this plate *l* completely fills the recess formed along the front edge of the door, thereby avoiding the formation of any ribs or other flanges or projections 70 along the front face of the door that would be liable to form dams for the collection of rain-water, whereby the liability of leakage or seepage at the front edge of the door is reduced to a minimum. It will be observed 75 that when the front edge of the door is moved to closed position, it fits within the groove formed between the flange *l* and the front face of the door-post member *J*, and, in order that the front edge of the door may 80 enter this groove with certainty and be forced or cammed against the front face of said post member *j*, the corner of the angle iron *d*, *f* is rounded off at *m*, and the inner corner of the free edge of *l* is rounded off 85 at *n*. To brace the post structure as well as the abutment plate *i*, I bolt to the outer face of the car-body a vertical beam or supplemental post member *o*, one face of this 90 post member abutting solidly against the adjacent face of the abutment plate *i*, this post being thick enough to extend approximately to the outer edge of said abutment plate. The abutment plate, extending into the body of the post structure as described 95 and shown, serves to not only afford a solid abutment for the door, but also serves to prevent seepage of water into the car through a path around the abutment plate, as is obvious.

Having thus described my invention, what I claim is—

The combination with a post of a box-car, said post having anchored to it an abutment plate whose front edge is provided 105 with a laterally extending flange to form a vertical groove for the front edge of the door, and a sliding door provided along its

front edge with an angle iron whose plates or flanges lie against the front edge of the door as well as against the front face of the door, the plate lying on the front face of the door being rabbeted into the face of the door and being provided along its free edge with an outwardly extending flange, said outwardly extending flange as well as the outer face of the flange of the abutment

plate lying approximately flush with the 10 face of the door.

In testimony whereof I hereunto affix my signature in the presence of two witnesses.

JAMES W. RUMSEY.
